UNITED STATES PATENT OFFICE.

RALPH H. PHILLIPS, OF RATHBONE, OKLAHOMA TERRITORY.

WINDMILL.

SPECIFICATION forming part of Letters Patent No. 767,080, dated August 9, 1904.

Application filed November 20, 1903. Serial No. 182,012. (No model.)

To all whom it may concern:

Be it known that I, RALPH H. PHILLIPS, a citizen of the United States, residing at Rathbone, in the county of Custer and Territory of 5 Oklahoma, have invented certain new and useful Improvements in Windmills, of which the following is a specification.

This invention belongs to the type of engines which utilize currents of air as the motive medium and to the variety employing a 10 motor-wheel arranged to rotate in a horizontal plane and about a vertical axis, a portion of the wheel being protected by a wind-guard and the opposite portion being exposed to receive the impact of the air-currents utilized 15 for operating the engine.

The improvement consists, essentially, of the novel manner of mounting the parts and the peculiar means devised for automatically 20 controlling the wind-guard, so as to adapt itself to the shifting currents of air, whereby the engine is continuously driven when required for work and there is in existence a current of air of sufficient strength to operate 25 the machine.

For a full description of the invention and the merits thereof and also to acquire a knowledge of the details of construction of the means for effecting the result reference is to be had 30 to the following description and drawings hereto attached.

While the essential and characteristic features of the invention are susceptible of modification, still the preferred embodiment of the 35 invention is illustrated in the accompanying drawings, in which—

Figure 1 is a perspective view of a wind-engine specially designed for attaining the objects of this invention. Fig. 2 is a horizontal section thereof on the line X X of Fig. 40 4. Fig. 3 is a top plan view of the engine. Fig. 4 is a vertical section on the line Y Y of Fig. 3.

Corresponding and like parts are referred 45 to in the following description and indicated in all the views of the drawings by the same reference characters.

The derrick or tower 1 may be of any construction to form a substantial support for 50 the operating parts and is provided at its up-

per end with a circular track 2, upon which is mounted a rotary frame or reel provided with the wind-guard 3, said frame having rotary supports or axes 4, arranged to travel upon the track 2. The shaft 5 of the engine 55 is journaled centrally of the derrick or tower and is mounted in antifriction or ball bearings, so as to minimize the resistance and reduce the friction to the smallest amount possible. The shaft 5 may be mounted in any 60 substantial manner and projects above the tower a distance to receive the motor-wheel, reel, and the vane for holding the engine in the wind.

The rotary frame or reel comprises a plurality of upper and lower crossed arms 6, connected at their outer ends by vertical bars 7. This reel is loosely mounted upon the shaft 5, so as not to interfere with the free rotation thereof when the engine is in operation and to move so as to adapt itself to the direction of the air-currents. The rotary supports or 70 caster-wheels 4 are secured to the lowermost arms of the reel or frame and are positioned so as to obtain a safe mounting upon the track 75 2 and to balance the reel thereon, whereby the shaft 5 is relieved of any strain incident to a leaning of the reel toward any particular side.

The wind-guard 3 is one-fourth of a circle 80 or thereabout and may be constructed of sheet metal or other material adapted for the purpose. The guard is arranged to cover one half of the forward portion of the wheel, thereby leaving the other half exposed, so as 85 to receive the action of the wind.

The vane 8 for automatically controlling the wind-guard may be of any construction and is mounted coaxially with the motor-wheel, preferably upon an extension of the 90 shaft 5. Bars 9 are secured at one end to the vane 8 and are loosely mounted at their other end upon the vertical extension of the shaft 5, so as to admit of independent movement of the vane without affecting the movements of 95 the motor wheel or reel. Cords or ropes 10 are connected to the vane 8 and project in opposite directions therefrom and pass through keepers 11 at opposite sides of the vane, thence over guide-pulleys 12, applied to the 100

reel, and are provided at their lower ends with weights 13, which hold the reel and wind-guard in proper position. The vane 8 when properly adjusted with reference to the wheel 5 and the guard is secured to the reel in any manner by fastening either one or both of the cords 10 thereto by suitable means. A curved track 14 connects upper adjacent arms of the reel and supports the wheel 15, secured to the 10 lower edge of the vane 8. As is well known, in engines of the type aforesaid the vane 8 always occupies a position parallel with the current of air and shifts with the direction of current, so as to hold the engine in the 15 wind or out of the wind, as may be determined upon. The vane 8 of the present invention performs the accustomed office and automatically shifts the wind-guard so as to cover one half of the forward portion of the 20 motor-wheel and leave the opposite forward half exposed for action of the air thereon.

The motor-wheel comprises corresponding upper and lower arms 16 and sails 17, which are connected at their upper and lower edges 25 to companion vertically-aligned arms and belly or curve intermediate of their upper and lower edges, so as to receive the full benefit of the current of air. The sails 17 may be of textile, sheet metal, or other suitable material for this 30 purpose and may be connected to the arms in any substantial manner. The arms 16 may be secured at their inner ends to the shaft 5 in any determinate way, preferably by being attached to hubs or collars 18, which are fast 35 to the shaft 5, in any way common in engines of this variety. The motor-wheel is arranged to operate wholly within the reel or rotary frame supporting the wind-guard; hence is in a measure protected thereby.

Having thus described the invention what 40 is claimed as new is—

1. In a wind-engine, the combination of a motor-wheel arranged to turn about a vertical axis, a wind-guard for protecting one-half of the forward portion of the motor-wheel, a 45 support for said wind-guard mounted coaxially with the motor-wheel, a governing-vane mounted coaxially with the motor-wheel and wind-guard support, flexible connections extended from opposite sides of the vane and 50 loosely connected with the wind-guard support at opposite sides of said vane, and weights applied to the lower ends of said flexible connections, substantially as specified.

2. The herein-described wind-engine comprising a derrick provided with a circular track, a vertical shaft journaled centrally of the derrick, a reel loosely mounted upon the shaft and provided with rotary supports to travel upon said circular track, a wind-guard 55 applied to a portion of the reel, a motor-wheel secured to said shaft and inclosed by said reel and comprising horizontal arms and vertical sails curved intermediate of their upper and lower edges, a vane loosely mounted upon the 60 shaft, a curved track and rotary support sustaining said vane, flexible connections projecting from opposite sides of the vane and loosely connected with portions of the reel, and weights applied to the lower ends of said 65 flexible connections, substantially as specified.

In testimony whereof I affix my signature in presence of two witnesses.

RALPH H. PHILLIPS. [L. S.]
